MULTIPLE SCALE RULER

Douglas D. Seely, Jr., 20138 Brick Road,
South Bend, Ind.

Continuation of design application Ser. No. 62,717,
Nov. 3, 1960. This application June 27, 1963, Ser. No.
75,585

Term of patent 14 years

(Cl. D52—6)

FIGURE 1 is a plan view of a multiple scale ruler, showing my new design;

FIGURE 2 is a cross sectional view thereof taken on line 2—2 of FIGURE 1;

FIGURE 3 is a fragmentary bottom view thereof; and

FIGURE 4 is an end elevational view looking from the upper right of FIGURE 1.

This is a continuation of my copending application Serial No. D. 62,717, filed November 3, 1960, and now abandoned.

I claim:

The ornamental design for a multiple scale ruler, substantially as shown.
